ELLA S. HALL AND ALEXANDER N. KAZNAKOFF, OF NEW YORK, N. Y.

THREAD-GUIDE GRIPPER.

Application filed June 6, 1921. Serial No. 475,258.

To all whom it may concern:

Be it known that we, ELLA S. HALL and ALEXANDER N. KAZNAKOFF, citizens, respectively, of the United States and Russia, and residents of the city of New York, borough of Manhattan, in the county and State of New York, have invented a new and Improved Thread-Guide Gripper, of which the following is a full, clear, and exact description.

This invention relates to a thread guide and support, and has for an object the provision of a simple, efficient, durable and economically manufactured device which can be attached to any type of thread spool whereby thread may be easily held to prevent unravelling of the thread from the spool.

The invention is illustrated in the drawings, of which—

Figure 1 is a perspective view of the spool with our device attached thereto;

Figure 2 is a side elevation partly in section of a spool with the device attached; and

Figure 3 is a perspective view of the attachment itself.

The preferred form of our invention, as shown in the drawings, is applicable to any type of thread spool, such as 1, on which thread 2 is wound. These spools are generally provided with an interior bore 3.

We provide a cap 4, made of any suitable sheet metal, in the form of a flat circular disk which has around its edges a downwardly projecting, crimped-over flange portion 5 (see Fig. 2). In order to hold this cap or disk 4 against one end of the spool 1, we provide a pair of spring fingers, such as 6, which are formed of one continuous piece of sheet metal and are adapted to extend downward into the bore 3 of the spool and grip the interior wall thereof. The upper ends of the spring fingers are bent in the form of a head portion 7 at right angles to the finger 6, and the ends of this head portion 7 are adapted to be gripped by the turned-over flange portion 5 of the disk 4. In forming the device, the cap 4 is formed without having the flanges 5 turned over. The head 7 of the spring fingers 6 is then placed within the cap, whereupon the flange 5 is crimped and turned over, and in being turned over the head portion 7 is gripped therebetween.

The fact that the cap 4 and the resilient spool-engaging member are made of a con-

tinuous integral piece of sheet metal and can be formed by machinery and assembled in the same manner makes this device which is composed of two simple parts, a very economical one to manufacture and which at the same time is strong and efficient in use.

As shown in Figure 2, the cap 4 is placed against one face of the spool with the finger 6 extending into the bore 3. The ends 8 of the thread are then slipped under the edge of the cap 4, which bears rather closely against the adjacent face of the spool, and is held or gripped firmly therebetween. This provides a simple and sure means of holding the ends of the thread to prevent unravelling of the thread from the spool.

It will be noticed in Figure 2 that the fingers 6 are bent and curved at a plurality of points, such as 9 and 10, to engage the walls of the bore 3 throughout the length of the fingers to give a more uniform gripping action. The ends 11 of the spring fingers 6, as shown in Figure 2 particularly, it will be observed, converge toward each other so that they touch only at their tips. The curvature at a plurality of points of the fingers, together with the tapered relation of their ends, insures at all times for the fingers the desired amount of resiliency whereby a sure and uniform gripping action will take place between the spring fingers and the walls of the spools. The tapered effect of the end 11 will also facilitate the entry of the device in the bore 3.

What we claim is:

1. An attachment for thread-carrying spools, which comprises a sheet metal cap adapted to be disposed adjacent one end face of the spool and having its edges curved over to form a flange portion, and a resilient single-piece spring extending from the cap into engagement with the bore of the spool, a portion of said spring being engaged by the edge of the cap.

2. An attachment for thread-carrying spools having an inner bore, which comprises a cap formed of a single piece of sheet metal having its outer edges curved over, a spring finger extending from said cap and adapted to engage the walls of the bore, and a head portion connected to said spring finger, the ends of the head portion gripped between the crimped-over edges of the cap, and a plurality of bore-engaging portions or projections on said finger.

3. An attachment for thread-carrying spools having a bore, which comprises a sheet metal cap formed of a single piece of material having its edges curved over, and 5 a pair of curved spring fingers extending from said cap into the bore to engage the walls thereof, said spring fingers having heads thereon adapted to lie along the inner 10 face of the cap, the ends of said heads being gripped between the curved-over edges of the cap.

4. An attachment for thread-carrying spools to hold the ends of the threads, which comprises a sheet metal cap adapted to be 15 disposed adjacent an end of the spool, said spool having a bore therein, and a pair of resilient spring fingers adapted to extend into the bore to engage the walls thereof, 20 said fingers each having a plurality of flared curved portions throughout its length

adapted to bear against and contact with the walls of the bore, the ends of the fingers tapering or converging toward each other at a slight angle.

5. An attachment for thread-carrying 25 spools, which comprises a sheet metal cap having its edges bent over in a smooth curve and adapted to bear against the end of the spool, a pair of spring fingers extending into the bore of the spool, said fingers having a 30 plurality of curved engaging portions throughout their length, the outer ends of the fingers converging toward each other whereby the ready entry of the device into the spool is effected, the end of the spool 35 being engaged by the turned-over edges of the cap.

ELLA S. HALL.

ALEXANDER N. KAZNAKOFF.
